UNITED STATES PATENT OFFICE.

WILLIAM A. McCLELLAND, OF RIDGEWOOD, NEW JERSEY.

BROILER HOOD.

Application filed February 16, 1922. Serial No. 536,857.

To all whom it may concern:

Be it known that I, WILLIAM A. McCLELLAND, a citizen of the United States, residing in Ridgewood, county of Bergen, State of New Jersey, have invented certain new and useful Improvements in Broiler Hoods, of which the following is a specification.

This invention relates to broiler hoods and has for one of its important objects the provision of a simple and inexpensive device of the character which is particularly adapted to be used in connection with an ordinary cook stove as a means whereby the fumes or odors arising from cooking foodstuffs may be entrapped or collected and thereafter directed into the stove from which they are passed into the flue and dissipated.

Other objects of the invention will become apparent from the following description taken in connection with the accompanying drawings in which:

Figure 1 is a perspective view of the device embodying my invention.

Figure 2 is a central vertical longitudinal sectional view of the device.

Figure 3 is a somewhat enlarged fragmental sectional view of an interlocking separable hinged connection.

In the drawings wherein is shown what I at present consider the preferred form of my invention, the numeral 5 indicates a base or bottom which is bent along its longitudinal edges to provide vertically disposed side walls 6, one of which is provided with a window 7 which is adapted to be opened or closed by means of a door 8 pivoted to the walls 6 as shown at 9 and provided with an outwardly extending handle 10 which projects through the opening 7 and serves as a means for limiting the swinging or pivotal movement of the door 8 when it is being either closed or opened. The base or bottom 5 is at its forward end bent to provide a flange 11 which overlies the lower ends of similar flanges 12 formed at the forward ends of the side members or walls 6. The flanges 11 and 12 are bent upon themselves as shown in Figure 2 and are adapted to be suitably connected at their overlying ends if desired to reinforce the structure and lend rigidity thereto.

A suitable cover 13 is attached to the upper edges of the walls 6, which cover is at its ends bent to form U-shaped flanges 14 into which the side members 6 are adapted to fit. The cover 13 is bent transversely to pro-

vide an apron 15 formed with U-shaped flanges 16 which are fitted over the inclined edges of the side walls 6. At the lower end of the apron 15 there is provided a U-shaped flange 17 into which the rear end of the base or bottom 5 is fitted.

With each of the side walls 6 there is associated a horizontally disposed guide 18, the vertically disposed flange 19 of which is inserted into the U-shaped flange 14. By employing suitable rivets 20 which are passed through the flanges 14, the flanges 19 of the horizontally disposed guides, and the upper edges of the side walls 6, it is obvious that a compact and rigid union may be effected between these several elements. It may be remarked here that if desired, the flanges 16 may be united with the side members 6 by riveting or any other suitable method and so also may the U-shaped flange 17 be suitably secured to the base or bottom 5.

The forward edge of the cover 13 is bent to provide an arcuate shaped hinge member 21, the end of which is bent to form an abutment 22. The hinge member 21 is adapted to support a hinged door 23 which is capable of being lifted in an arc and thereafter moved horizontally along the guide members 18. The upper end of the door or closure 23 is bent to provide an arcuate shaped hinge portion 24 the end of which is formed with a flange 25 adapted to contact with the flange or abutment 22 when the door or closure 23 is maintained in a normal position. From an inspection of Figure 3 it is obvious that when the door or closure 23 is swung about its pivotal connection with the hinge member 21 the door will assume such a position as will permit the hinge portion 24 to disengage the hinge portion 21 whereby the door may be moved horizontally along the guides 18 to the position shown in Figure 1. It will be noted that the door or closure 23 is of such a length as to provide a clearance between the lower end thereof and the flange 11 when maintained in the position shown in Figure 2. The clearance thus provided permits a draft to enter the apparatus in order that the removal of the fumes or odors given off by the cooking foodstuff may be facilitated.

The apparatus embodying my invention is intended to be placed on an ordinary cook stove in such a manner that the relatively large opening 26 formed in the base 5 and

over which the broiling or cooking is intended to be done, may register with one of the holes in the top of the stove, whereas the other opening 27 formed in the base or bottom 5, is intended to register with another opening or hole in the top of the stove. In placing the apparatus on the stove the opening 26 is placed preferably over one of the openings in the top of the stove which 10 communicates with the fire box thereof and the opening 27 is preferably placed over a hole or opening near the pipe or flue connection inasmuch as this arrangement tends to produce or create a relatively strong draft 15 through the apparatus.

In use the broiling is done over the opening 26 and by reason of the draft created through the apparatus any fumes or odors given off during the cooking are drawn into 20 the cook stove through the opening 27 from which they are passed into the flue and dissipated. The door or closure 23 may be maintained in the position shown in Figure 2 during the cooking operation but if it is 25 desired to observe the condition of the food while being cooked or remove the same from the apparatus the door may be lifted and thereafter moved along the guides 18 shown in Figure 1. If more light is desired to determine the condition of the food which is 30 being cooked it may sometimes happen that by opening the closure 8 additional light may be allowed to enter. The door or closure 35 8 may be opened also to permit a greater volume of air to enter the apparatus to more effectively carry off the fumes or odors of the food-stuff which is being cooked.

As a means for facilitating the opening or closing of the door or closure 23, I provide 40 a handle 28 at the lower end thereof and in order to facilitate handling of the apparatus as a whole I employ a handle 29 which is secured preferably to the apron 15.

In many households a fire is not maintained in the range or cook stove during the 45 summer months at which time the cooking is usually done on an oil or gas stove with which my apparatus is not particularly adapted to be used. In order that the device may be used in connection with the stove without necessitating the maintenance of a fire therein I provide a perforated fire pot 30 which is adapted to fit into the opening 26 in such a manner that the flange 31 50 of the pot rests upon the base or bottom adjacent the opening 26. Into the pot 30 a suitable quantity of charcoal may be placed which when burned will offer a sufficient amount of heat to enable the broiling or 60 cooking process to be carried out. It may be mentioned that the pot 30 is adapted to extend into the fire box of the stove when the apparatus is placed therein in the position above mentioned in which position the cooking 65 fumes are carried rearwardly through

the apparatus from which they pass into the stove through the opening 27 and are dissipated.

While I have described the apparatus embodying my invention as being particularly adapted to be used when broiling, it is understood that it is in many cases equally well adapted to be used when cooking by other methods. It is also obvious that various changes in the size, arrangement and construction of the various elements entering into the combination embodying my invention may be resorted to without departing from the spirit of the invention or the scope of the subjoined claims.

Having thus described my invention, I claim:

1. A cooking hood adapted to be used in connection with a cook stove comprising a box-like structure having an opening adapted to register with an opening in the top of the stove over which the cooking is done and further provided with an exit opening adapted to register with another opening in the top of the stove through which the cooking odors are adapted to be expelled, an arcuate shaped hinge member carried at one end of the box-like structure, and a door closure having closure supporting guides arranged within said box-like structure, a hinge portion normally interlocking with said hinge member but releasable therefrom, said closure being adapted to be swung about the axis of said hinge portion to sever its interlocking engagement with said hinge member to permit said closure to be thereafter moved rearwardly into said box like structure over said guides.

2. A cooking hood adapted to be used in connection with a cook stove comprising a box-like structure having a bottom provided with an opening adapted to register with an opening in the top of the stove over which the cooking is done and further provided with an exit opening adapted to register with another opening in the top of the stove through which the cooking odors are adapted to be expelled, a top for said box-like structure, said top being at its forward end bent to provide an arcuate shape hinge member, closure supporting guides arranged within said box-like structure, a closure for said box-like structure, said closure being at one edge bent to provide an arcuate shape hinge portion adapted to co-operate with said hinge member and form therewith an interlocking hinge engagement between the box-like structure and the closure, said closure being adapted to be moved to sever its hinge engagement with said box-like structure and thereafter moved rearwardly into said structure over said guides.

In testimony whereof, I have affixed my signature to this specification.

WILLIAM A. McCLELLAND.
